UNITED STATES PATENT OFFICE.

COLUMBUS T. COOPER, OF ANDERSON, SOUTH CAROLINA, ASSIGNOR OF ONE-HALF TO
WILLIAM M. SHERARD, OF IVA, SOUTH CAROLINA.

WARPER ATTACHMENT.

Refiled for abandoned application Serial No. 555,765, filed April 16, 1910. This application filed September 11, 1924. Serial No. 737,217.

To all whom it may concern:

Be it known that I, COLUMBUS T. COOPER, a citizen of the United States, residing at Anderson, in the county of Anderson and 5 State of South Carolina, have invented new and useful Improvements in Warper Attachments, of which the following is a specification.

This application is refiled for abandoned 10 application No. 555,765, filed Apr. 16, 1910.

This invention relates to warpers and has for its principal object to provide means whereby the loose lint from the threads will be prevented from settling on the drop 15 wires, combs, and drop wire bars of the warper so as to materially increase the efficiency of the warper and insure a production of a perfect product from the warper.

A further object of the invention is the 20 provision of an extremely simple, efficient and practical device of the character referred to in the nature of a fan so arranged as to distribute a blast of air over the parts on which the lint or short fibers from the 25 threads usually settle so as to keep the said parts at all times free from settling.

Another object of the invention is to provide a blast device of such a design that it can be used as an attachment for machines 30 now in use without requiring any alteration therein, the fan being driven by one of the rotating parts of the warper.

With these objects in view and others as will appear as the description proceeds, the 35 invention comprises the various novel features of construction and arrangement of parts which will be more fully described hereinafter and set forth with particularity in the claims appended hereto.

40 In the accompanying drawing, which illustrates an embodiment of the invention:—

Figure 1 is a front elevation of the attachment applied to the end of a warper.

Figure 2 is a side view of Figure 1.

Figure 3 is a plan view of the air distributing means.

Figure 4 is an enlarged detail view in elevation of the air distributing means.

Similar reference characters are employed 50 to designate corresponding parts throughout the several views.

The difficulties in the operation of warpers designed to be overcome by the present invention will be first described before entering into a detail description of the invention. 55

A beam warper carries anywhere from 300 to 500 ends of yarn, and each of these threads passes through a separate drop-wire, and dent in the comb. These threads pass through these wires and dents at a rate of 60 sixty yards per minute, and there is an enormous amount of short fibres or lint chaffing off the threads settling on the wires and bars, and also the comb boxes, especially 65 between the front comb box and front drop-wire bars which form a groove or trough about one and one-half inches deep and sixty inches long. In this groove or trough is where the principal part of the trouble is with warpers catching lint and other 70 foreign substance, although the lint settling on drop wires causes them to choke up and not fall when a thread breaks. These wires are about two inches long and one sixteenth in diameter, and are set at an angle of about 75 sixty degrees. These wires work automatically and when they are free from lint will stop the machine when an end breaks down.

If the machine fails to stop, as is usually 80 the case in many instances, then the work is very badly damaged and causes imperfect goods when it reaches the looms. The threads on warpers pass directly over the grooves mentioned above, and 85

the chaffing of the yarn soon causes the groove to fill up until it comes in contact with the yarn. Just as soon as one of the ends touches this lint, it causes the whole amount in this groove to link together, and as it comes in contact with the yarn, will 90 cause fully nine-tenths of the threads to carry a large bunch of loose lint. After leaving the warpers, the yarn goes to the slasher room, and the large bunches of loose 95 lint is run through the sizing kettles which gives it a firm hold on the good work and when it reaches the looms it usually causes a number of threads on each side to lap up and damage the goods very materially.

100 Referring to the drawing, A designates a rotary fan or blower, which is mounted on one end 1 of the frame of a beam warper,

the fan consisting of a wheel 2 rotatably mounted in a casing 3 that is provided with a bracket 4 bolted to the frame 1 at the belt end thereof. The wheel is mounted on a 5 shaft 5, which is provided with a pulley 6 around which the belt 7 passes. This belt also passes around a large pulley 8 on the top cone shaft of the warper, which shaft is driven by gearing 9 from the driving 10 shaft 10 on which the usual belt pulleys 11 are mounted. The belt 7 crosses at a point adjacent the smaller pulley 6 so that a maximum area of contact will be obtained between the pulley and belt to thus avoid 15 slipping, it being understood that the speed of rotation of the fan is considerable since the cone shaft makes about four hundred and twenty revolutions per minute.

The fan supplies air to a distributing device B arranged at the top of the end portion of the frame 1 and this device is connected by a duct 12 with the fan casing so that air will be forced by the fan wheel from the duct and distributed by the device B 20 over those parts of the warper that are liable to be clogged by lint or fiber chaffed off from the fast traveling threads. The device B consists of an elbow 13 arranged on the upper end of the duct 12 and so positioned that the arm of the elbow that discharges the air will be disposed horizontally at the top of the machine, the said elbow being supported by a bracket 14 which is secured to the upper part of the frame 1. 25 As the area to be cleaned or kept free from lint or fiber is about twenty inches wide and sixty inches long, it is necessary to provide an air deflecting means so that the blast delivered from the fan will be effectively 30 distributed to play on the drop wires, combs, drop wire bars. For this purpose a vane 15 is arranged directly in front of the discharge nozzle or elbow 13 and is adapted to have an oscillatory or rocking movement so 35 as to deflect the air over the desired area. The vane is supported on a vertical rock shaft 16 journaled in arms 17 on the bracket 14 and this shaft has a crank arm 18 that is connected by a link 19 with a crank arm 40 20 which is secured to the stop-motion rod 21 of the warper. Hence as the rod 21 rocks the arm 20 will swing back and forth and cause the fan-carrying shaft to rock and in this manner the air will be regularly 45 distributed over the parts to be cleaned.

From the foregoing description taken in connection with the accompanying drawings, the advantages of the construction and the method of operation will be readily apparent to those skilled in the art to which the invention relates, and while I have described the principle of operation of the invention, together with the device which I now consider to be the best embodiment 60 thereof, I desire to have it understood that

the device shown is merely illustrative and that such changes may be made when desired as are within the scope of the claims.

Having described the invention, I claim:

1. The combination of a warper including an element having a rotary back and forth movement, with a blast producing device including a discharge nozzle arranged to direct a blast against the drop wires and adjacent parts of the warper, a device mounted on the warper and arranged in the blast for distributing the same over a wide area of the warper, and an operating connection between the said element and last mentioned device for operating the latter.

2. The combination of a warper, a blast producing device mounted thereon, means for driving the device by a moving part of the warper, said device including discharging means arranged adjacent the drop wires and adjacent parts of the warper, and a distributing means disposed in cooperative relation with the discharging means and operated by a moving part of the warper for distributing the blast over the drop wires and adjacent parts to be cleaned.

3. The combination of a warper, means for driving the fan by a moving part of the warper, an air duct connected with the fan, a nozzle on the duct arranged to direct a blast of air against the drop wires and adjacent parts of the warper, and a vane mounted in front of the nozzle and automatically actuated to distribute the air over the parts to be cleaned.

4. The combination of a warper including a stop-motion rod, a blast producing device having a nozzle arranged to direct air on the warper, and a deflector arranged in cooperative relation with the said device and operatively connected with the said rod to distribute the blast over different parts of the machine.

5. The combination of a warper including a cone shaft and a stop-motion rod, with a blast-producing device including a fan, driving means between the cone shaft and fan, and means actuated by the stop-motion rod to distribute the air delivered by the fan over the drop wires, combs and drop-wire bars of the warper.

6. In a warper, the combination of a cone shaft, means for driving the same, a fan, means for driving the fan by the cone shaft, a duct connected with the fan, a nozzle on the duct arranged to discharge a blast of air, a stop motion rod, and an automatically actuated device connected with said rod for distributing the air from the nozzle over the parts of the warper on which lint is liable to settle.

7. In a warper, the combination of a cone shaft, means for driving the same, a fan mounted on the frame of the warper, means

for driving the fan by the cone shaft, a duct connected with the fan, a nozzle on the duct arranged to discharge a blast of air, a distributing vane arranged in cooperative relation with the nozzle for distributing the air over those portions of the warper liable to be obstructed by lint, means for mounting the vane on the frame of the warper, a stop motion rod, and means for connecting the

rod with the vane for actuating the latter.

8. In a warper, the combination of a device mounted to discharge a blast of air against the drop wires and adjacent parts of the warper, a vane disposed in front of the device to distribute the air over a wide area, a rock shaft on which the vane is mounted,

a stop-motion rod, and means between the rod and shaft for rocking the said shaft.

9. In a warper, the combination of a device mounted to discharge a blast of air against the drop wires and adjacent parts of the warper, a vane disposed in front of the device to distribute the air over the wide area, a rock shaft, on which the vane is mounted, a stop-motion rod, a crank arm on the rock shaft, an arm on the said rod, and a connection between the said arms whereby the stop-motion rod rocks the said shaft.

In testimony whereof I affix my signature

COLUMBUS T. COOPER.
